UNITED STATES PATENT OFFICE.

ELVIN D. MORTON, OF INDIANAPOLIS, INDIANA.

DESIGN FOR A SPEEDWAY-BODY FOR MOTOR-VEHICLES OF THE FORD TYPE.

54,668.

Specification for Design.

Patented Mar. 9, 1920.

Application filed September 20, 1919. Serial No. 325,278. Term of patent 3½ years.

To all whom it may concern:

Be it known that I, ELVIN D. MORTON, a citizen of Canada, residing at Indianapolis, in the county of Marion and State of Indiana, have invented a new, original, and ornamental Design for a Speedway-Body for Motor-Vehicles of the Ford Type, of which the following is a specification, reference being had to the accompanying drawing, forming part thereof.

Figure 1 is side view.

Fig. 2 is plan view.

Fig. 3 is front view.

I claim:

The ornamental design for a speedway body for motor vehicles of the Ford type, as shown.

In testimony whereof I affix my signature in the presence of two witnesses.

ELVIN D. MORTON.

Witnesses:

JEWEL CLARK,
JACK BRETT.
